UNITED STATES PATENT OFFICE

HEINRICH SIEPRATH, OF AACHEN, GERMANY

LAMINATED SPRING

Application filed November 3, 1928, Serial No. 317,063, and in Germany July 21, 1927.

This invention relates to a suspension spring, particularly for railway vehicles and it has for its object to provide means for coupling the spring plates rigidly and immovably to the spring buckle, so as to prevent displacement of said spring plates relatively to said buckle when the vehicle is in operation.

Numerous kinds of fastening means for the spring buckle are known but most of these have been frictional connections, that is to say, the spring buckle was fastened by means of keys or cotters or by pressing or shrinking it on to the plates. It is found in practice that such fixing means work loose in a short time under the influence of the shocks which occur in working the vehicle. Fastening devices are also known in which rigid connection between the spring plates and the spring buckle is actually obtained but also at the expense of strength in the spring itself, or else it is necessary, when disassembling the connection to destroy some part or parts. Thus, the strength of the spring has been weakened when the spring plates were drilled through or furnished with lateral recesses, or undulating bends, or when the spring buckle was divided, slotted, drilled through or included curvilinear deflections. There are again, methods of fastening which demand such a high degree of precision in the manufacture of the spring that, in addition to the drawback mentioned above, there is no prospect of making them on an economic basis.

Hence, the problem to be solved is the provision of a spring which satisfies the requirements of railway working and the manufacturing requirements also. The spring plates must not be weakened in cross-section by drilling them through, recessing them or giving them undulating bends, the spring buckle must remain undivided and unweakened and all the parts of the spring and its fastening must be capable of being pro-

duced in the simplest form and as cheaply as possible and must also be interchangeable. In accordance with the invention it is also essential to obtain, in conjunction with the advantages aforesaid, a firm, immovable connection between the spring buckle and the spring plates.

All these requirements are fully met by the present invention. The construction of the spring and the manner in which it works can be seen in the accompanying drawings, in which:

Fig. 1 is a side elevation of the spring buckle and part of the spring.

Fig. 2 is a central section through the spring on line C—D of Fig. 1.

Fig. 3 is a part sectional plan view taken on line A—B of Fig. 1.

Fig. 4 shows the coupling plate in side elevation and

Fig. 5 the same in plan view.

The laminated spring is composed of spring plates *b* having each in its upper face a longitudinal groove *a* and at its bottom face a longitudinal rib engaging the groove of the plate below it, while said groove is engaged by the longitudinal rib of the plate above it. The central portion of each groove is considerably larger and deeper and forms a cavity or depression *d*, and just so the central portion of each rib forms a downwardly directed boss *d* which engages the depression below it, while the depression located just above and pertaining to the plate having that boss is engaged by the boss of the plate above it.

In building up the spring, the spring plates *b* are arranged in layers, one on top of another and interengaged by means of the bosses *d* and boss depressions *d*. The lowest spring plate has its boss fitted into a corresponding boss depression in the bottom of the spring buckle *c*. On the uppermost spring plate lies the coupling plate *e*, the central boss *d* of which engages in the boss depression *d* of said plate while lateral lugs *f* on said cou-

pling plate co-operate with the cheeks of the spring buckle *c* to keep said coupling plate in position. The free space above the coupling plate is filled up with a liner plate *g* which holds the bundle of springs in engagement with the plate *e*.

Assembly is effected by drawing the locking member, already inserted in the spring buckle, over the packet of springs, previously bundled and bound together by clamping devices until the middle is reached. The boss on the lowermost spring plate then springs into the boss depression of the spring buckle and the boss of the coupling plate into the boss rest on the uppermost spring plate. In order to fill up the free space between the coupling plate and the inner side of the spring buckle and to keep the bosses constantly in engagement the supplementary liner *g* is driven in. No separate fastening of the latter is necessary since it is not subjected to any horizontal displacing forces.

The spring plates are now firmly connected to the buckle, since the main spring plate, to which the horizontal forces are applied, when the spring is working, is immovably coupled to the spring buckle by the boss *d* and the lugs *f*, while all the other plates are interconnected and connected to the lower part of the buckle by bosses and boss depressions. Lack of safety in the working of the vehicle, in so far as the springs are concerned is thus, effectively overcome by the present invention.

In order to secure the lining plate in the spring buckle any kind of arrangement may be applied as only the accidental dropping out of this plate need be secured. No strains whatever are exerted on the lining plate. In the preferred form of the invention the fastening of said lining (packing) plate has been arranged in such a way that the one end *g'* is set off, and in consequence close to the upper horizontal cheek of the spring buckle *c*, the other end of the lining (packing) plate being horizontally slotted and one end *a''* bent upwards. An accidental dropping of the lining (packing) plate out of the buckle has been prevented that way.

Disassembly of the spring is effected by carrying out the operations of assembly in reverse order. The spring can be taken apart without damaging any of the parts.

The drawings show by way of example, only one possible form of construction and it is to be understood that constructional variations or mechanical inversions are not excluded from the scope of the invention.

What I claim is:—

A laminated spring, comprising, in combination, a plurality of superposed elastic plates having each on one of its faces a projection located in the center portion of the plate, and in its other face a cavity also located in the center portion of the plate and

adapted to receive the projection of the adjacent plates; a coupling plate contacting with one of the outermost plates of the set of plates and having at its four corners lateral lugs extending beyond the adjacent plate; a liner plate contacting with said coupling plate, and a buckle encompassing all said members and having its lateral parts located between said lugs.

In testimony whereof I have hereunto set my hand.

HEINRICH SIEPRATH.
